UNITED STATES PATENT OFFICE.

LORENZ DOBMEIER, OF BUFFALO, NEW YORK.

DESIGN FOR A SHOE-SCRAPER.

49,178.

Specification for Design.

Patented June 13, 1916.

Application filed April 7, 1916. Serial No. 89,717. Term of patent 3½ years.

To all whom it may concern:

Be it known that I, LORENZ DOBMEIER, a citizen of the United States, residing at Buffalo, in the county of Erie and State of New York, have invented a new, original, and ornamental Design for Shoe-Scrapers, of which the following is a specification, reference being had to the accompanying drawing, forming part thereof.

The figure is a perspective view of a shoe scraper showing my new design.

I claim:

The ornamental design for a shoe scraper, as shown.

LORENZ DOBMEIER.
